UNITED STATES PATENT OFFICE.

JAMES H. McCONNELL, OF EVANSTON, ILLINOIS.

DESIGN FOR A FEATHER DUSTER.

SPECIFICATION forming part of Design No. 35,529, dated December 31, 1901.

Application filed April 5, 1901. Serial No. 54,543. Term of patent 7 years.

To all whom it may concern:

Be it known that I, JAMES H. McCONNELL, a citizen of the United States, residing at Evanston, in the county of Cook, State of Illinois, have invented and produced a new and original Design for Feather Dusters, of which the following is a specification, reference being had to the accompanying drawing, forming a part hereof.

The accompanying drawing illustrates a feather duster embodying my design.

The skirt *b* of the duster *A* is bell-shaped, as shown, being formed of outwardly-curved feathers. These feathers are arranged in layers, with the outwardly-curving tips *a* of the successive layers at different distances from the bottom of the duster, those of the outermost layer being at the greatest distance from the bottom. Hence the lower portion of the

duster flares outwardly in curved lines, with 20 the outwardly-flaring tips of the successive layers of feathers arranged at the bottom of the duster, as shown, in different planes, giving to the duster a distinctive and attractive appearance.

Having thus described my invention, what I claim as new, and desire to secure by Letters Patent, is—

The design for a feather duster, as herein shown and described.

In testimony whereof I have signed my name to this specification in the presence of two subscribing witnesses.

JAMES H. McCONNELL.
